CLAIM

The ornamental design for “a spherical hand-held grip aid device for hand instrument manipulation,” as shown and described.

DESCRIPTION

FIG. 1 is a side, top, bottom and front perspective view of this spherical hand-held grip aid device for hand instrument manipulation showing my new design;

FIG. 2 is a side, top, bottom and front perspective view thereof;

FIG. 3 is a top view thereof;

FIG. 4 is a side view thereof;

FIG. 5 is a bottom view thereof;

FIG. 6 is a side view thereof;

FIG. 7 is a front view thereof; and,

FIG. 8 is a back view thereof.

The broken lines showing the hand and the spoon represent the environment in which the article resides and forms no part of the claimed design.

1 Claim, 5 Drawing Sheets
